UNITED STATES PATENT OFFICE

WILLIAM F. RICHARDS, OF MASON, MICHIGAN, ASSIGNOR TO S. M. A. CORPORATION,
OF CLEVELAND, OHIO, A CORPORATION OF OHIO

BAFFLE

Application filed August 23, 1930. Serial No. 477,237.

This invention relates to baffles for spray driers used for drying liquid materials, such as milk products or the like. The invention is an improvement upon that described and claimed in my prior patent for baffle granted June 17, 1930, No. 1,764,983, to which reference may be had, if desired, for a more complete description of what may be only briefly referred to here.

10 The object of the present invention is to generally improve the baffle, making it stronger and simpler in construction, and with its baffling or deflecting vanes well supported, and more efficient in directing air movement and sweeping off the deposited material therefrom, as will more fully appear hereinafter.

Further objects of the invention are in part obvious and in part will appear more in 20 detail hereinafter.

In the drawing, which represents one suitable embodiment of the invention, Fig. 1 is an outside elevation, partly in sectional elevation through the central axis, and illustrating a baffle applied in use; Fig. 2 is a plan view of the baffle alone; Fig. 3 is in part a side elevation and in part a section on the line 3—3, Fig. 2; Fig. 4 is a sectional plan view on the line 4—4, Fig. 3; Fig. 5 is a detail elevation, on a larger scale, looking edge-wise toward several adjoining baffling vanes; and Figs. 6, 7 and 8 are sectional elevations, respectively, on the lines 6—6, 7—7 and 8—8, Fig. 2.

35 As in my prior patent, the baffle to be described is utilized with a dry room embodying a chamber 1 to which heated air is applied for drying purposes through a conduit 2 having an air supply part 3 within the drying chamber 1. The air supply part 3 of the conduit, lying within the chamber, is rotatable about the central vertical axis because of its attachment to an operating shaft 5 rotated by a suitable driver 6, and the conduit 3 forms a support for the baffle, indicated generally at 7, Fig. 1. Said baffle, as in my prior patent, serves to deflect the air stream and distribute it throughout the drying chamber, so that it flows evenly to all parts 45 of the same and produces uniform drying results. The baffle is arranged to prevent or to minimize so far as possible the deposit of dried material upon its surfaces, to thereby prevent overheating or burning of such material and contamination of the entire mass 55 in case the burned product is mixed therewith.

The baffle forming the subject matter of the present invention comprises a central support made of two half tube sections 8, 60 which may be made by splitting a section of pipe longitudinally for more convenient assembly of the baffle as a whole. To each of the pipe sections 8 are attached a series of sheet metal vanes 9, each of generally triangular form with the vertical edges suitably attached to the pipe sections, such as by being provided with small flanges riveted or brazed thereto, as in my prior patent. The outer edges of the vanes are inclined upwardly and outwardly. In other words, the baffle, viewed in elevation, is like an inverted cone. The several vanes all lie in vertical planes extending radially outwardly from the central axis. At their upper edges the 70 several vanes are bent laterally in curved form, as shown in Fig. 5, so that the free horizontal upper edge of each vane slightly overlaps the vertical wall of the next vane. The curvature of bend of the horizontal fin 75 portions 9a thus formed is on approximately a 90° arc of a circle, with a radius of curvature decreasing from the outer edges toward the central vertical axis, as will appear upon comparison of Figs. 6, 7 and 8. As a result, 80 the slots or openings presented horizontally between the upper horizontal edge of each vane and the surface of the neighboring vane increases in width from the central axis outwardly and is quite wide at its outermost 90 point. This arrangement very largely increases the area of the said mouths or openings, offering less obstruction to the passage of air through or between the vanes of the baffle, and the curvature of the walls or fins 95 assists in gradually deflecting the air current to produce outward or spiral motion. Moreover, since more air flows upwardly between each two neighboring vanes of the baffle the sweeping effect of the air current, 100

by which material which otherwise might lodge upon the baffle, is swept off from its vanes, is materially increased.

For strengthening the structure I provide 5 an annulus extending around the baffle at any suitable point, say about midway of its height and connecting vane to vane at a point outwardly from the central axis. This annulus may extend around the outer edges of 10 the vanes, but as shown it is in the form of a round bar 10 bent to pass through openings in the succeeding vanes of the baffle and rigidly secured to each of them in any suitable manner, such as by brazing. Preferably, 15 the annulus 10 is split at two points along the plane of the parting of the tube sections 8, so that the baffle as a whole can be made in two parts for securing to each other. For fastening the two halves of the baffle together the tube parts 8 may be provided with short extensions around which split clamping 20 collars 11 may be clamped.

As in my prior patent this baffle is supported by the rotating inlet tube 3, such as 25 by bars 12 attached to either the vanes or tube members of the baffle and secured to the tube 3. Air flows freely through the tube and its upper end may be baffled by a small 30 perforated cone 13. To increase the flow of air upwardly through the hollow tubular support 8 I may provide its lower end with an air collector 14, which, for example, may be made of a piece of sheet metal bent to funnel or cornucopia form with its edges 35 overlapping, said collector being suitably attached to the support 8, as by bolts or rivets 15. With this arrangement, and especially with light sheet metal, the amount of flare may be adjusted as desired, as with 40 a paper cornucopia, until the inverted funnel thereby formed increases the effective area at the bottom of pipe 8 to any degree. In this manner more or less air may be caused to flow upwardly through pipe 8 to insure that 45 both said pipe and the cone 13 are kept free of powder deposits.

While the baffle shown is mounted upon and rotates with the air inlet pipe 3, this is 50 not essential, as the baffle may be independently mounted and may even be carried on ball bearings so that it rotates freely by the propelling force of the upwardly moving air stream.

What I claim is:

55 1. A baffle for spray driers, comprising a vertically disposed member having a central axis, a series of radial vanes attached to said member and each arranged in a plane passing through the central axis, the upper edges of said vanes being curved laterally to form a series of fins overlapping each other and presenting horizontal mouths or openings, said fins being connected to the vertical portions of the vanes by curved parts which

gradually deflect the air current through said mouths.

2. A baffle of the form described in claim 1, in which the curved portions of the vanes are curved on radii which increase outwardly 70 from the central axis.

3. A baffle of the form described in claim 1, in which the said mouths increase in width from the central axis outwardly.

In testimony whereof I hereby affix my 75 signature.

WILLIAM F. RICHARDS.
